Application August 10, 1943, Serial No. 498,073

2 Claims. (Cl. 242—4)

This invention relates to distributor mechanisms and more particularly to a distributor for toroidal coil winding machines.

It is an object of the present invention to provide a simple, easily adjustable distributor for a coil winding apparatus.

In accordance with one embodiment of the invention, a supporting clamp carrying a rectangular core with one side of the core disposed within a winding ring of the toroidal winding apparatus may be reciprocated by a distributor bar carrying a cam roller in the slot of a slotted cam member, pivotally mounted on a screw actuated plate, whereby the angle of the slotted cam member may be adjusted to predetermine the application of a winding on the core.

A complete understanding of the invention may be had by reference to the following detailed description of one embodiment thereof when considered in conjunction with the accompanying drawings, wherein

Fig. 1 is a plan view of a portion of a coil winding mechanism having a distributor connected thereto in accordance with the present invention;

Fig. 2 is a longitudinal sectional view taken substantially along the line 2—2 of Fig. 1 in the direction of the arrows; and

Fig. 3 is an end elevational view of the apparatus shown in plan in Fig. 1.

In the drawings, the apparatus is shown mounted upon a base 10 comprising a part of any suitable winding mechanism having bearing brackets 11 and 12 mounted thereon for rotatably supporting a drive shaft 13 and a winding ring 14 equipped with a suitable shuttle mechanism (not shown). Extending upwardly from the bracket 12 are a pair of arms 15 and 16, which support suitable guides for directing a strand from the winding ring 14 to a core 17 and also serve to support guide rollers 18 and 19, on which the winding ring is carried. The arm 16 of the bracket 12 serves as the bearing for the shaft 13 on which a driving gear 20 is supported with its teeth in mesh formed on the inner annular surface of the winding ring 14. Also mounted upon the shaft 13 is a drive pulley 21, adapted to be driven by a belt 22, which may, in turn, be connected to any suitable driving mechanism (not shown). In this manner, rotation may be imparted to the winding ring 14 to wind a serving of wire on the side of the core, which extends through the ring 14.

The right end of the shaft 13 has a hand wheel 23 fixed to it whereby rotation may be imparted manually to the ring 14. Intermediate the pulley 21 and the hand wheel 23, the shaft 13 carries a worm 24 in mesh with a worm gear 25, which is freely rotatable about a sleeve 26 encircling and keyed to a shaft 27 by means of the key 28. A pair of bearings 29 and 30 support the sleeve 26,

the bearing 29 surrounding the sleeve at its larger portion, which is provided with threads, as shown at 31. A reduced portion 32 of the sleeve 26 extends into the bearing 30 and the shoulder formed at the juncture of the larger portion of the sleeve with the reduced portion 32 serving to hold the sleeve in the bearings. The right end (Fig. 2) of the sleeve 26 has a flange 33 formed on it which serves to retain the worm gear 25 in alignment with the worm 24, the flange 33 extending into a shoulder portion 34 surrounding the central aperture in the gear 25. The right face of the gear 25, as shown in Fig. 2, is provided with clutch teeth 35—35, adapted to cooperate with clutch teeth 36—36 formed on a clutch member 37. The clutch member 37 is pinned to the shaft 27 by means of a pin 38 (Fig. 1) and is provided with a pair of cooperating shoulders 39 and 40, between which an eccentric pin 41 extends. The pin 41 is mounted eccentrically of a stud shaft 42, extending through a side plate 43 and adapted to be manipulated by a handle 44 attached to it. Rotation of the stud shaft 42 by the handle 44 will cause the pin 41 to move the clutch member 37 from the position shown, where a clutch member 45 on the left end (Fig. 2) of the shaft 27 engages with clutch teeth 46—46 formed on the reduced portion 32 of the sleeve 26. When the handle 44 is manipulated to shift the clutch member 37 from the position shown to its opposite position, the clutch member 45 will be disengaged from the teeth 46—46 and the clutch member 37 will be meshed with the teeth 35—35 on the worm gear 25. The shaft 27 has a bevelled gear 47 attached to it, which meshes with a companion bevelled gear 48 mounted on a manually operable shaft 49, which may be rotated by means of a handle 50. From the foregoing, it is believed to be apparent that the sleeve 35 may be driven by either the worm gear 25 or by the shaft 49, depending upon the position to which the shaft 27 is shifted, and depending upon whether clutch member 45 or clutch member 37 is engaged with the gear 25 or reduced portion 32 of the sleeve 26, respectively.

The bearings 29 and 30 are mounted upon a plate 60, mounted in spaced relation to the base 10 by a pair of supports 61 and 62, between which there is positioned a switch 63 fixed to the underside of the plate 60. A bracket 64, also fixed to the underside of the plate 60, pivotally supports a lever 65, carrying one end in alignment with a switch actuating plunger 66 and the other end in the path of a travelling nut 67, threadedly engaging the threads 31 on the sleeve 26. The switch 63 is connected in circuit to the motor (not shown) and will break the motor circuit when its plunger 66 is moved to the right (Fig. 2) due to the travelling nut 67 striking the lever 65 at the end of its travel to the left (Fig. 2). The travelling nut 67 is fixed to the underside of a carriage member 70, which is slidably mounted in the ways

71 and 72 (Fig. 3). The ways 71 and 72 are formed in the side plate 43 and an intermediate plate 73, in which the carriage 70 is held by a keeper 74. The carriage 70 is cut away, as shown at 75, to slidably position a slide member 76 for movement longitudinally and transversely of the carriage. The slide member 76 is rigidly connected to a core supporting block 77 (Fig. 3), which is slidable in ways 78 and 79 and carries a core clamping plate 80 removably attached thereto by means of a thumb nut 81.

From the foregoing, it is believed to be apparent that the core supporting block 77 and core clamping plate 80 may be moved from the position shown in full lines (Fig. 1) to the position shown in dot and dash lines (Fig. 1) to move the core 17 from its full line to its dotted line position while a winding is being applied to the core from the winding ring 14 and that the reciprocation of the core supporting block 77 and its cooperating clamping plate 80 may be effected by reciprocating the slide 76. In addition to the guiding means for the core supporting block 77, the right end of the slide 76 is slidably mounted in a slot 82 cut in the side plate 43 and a slot 83 cut into way 73, and thus the slide 76 may be reciprocated with respect to the carriage 70 (Fig. 1) and the carriage 70 may travel transversely of the direction of reciprocation of the slide.

The slide 76 carries a cam roller 90 extending from its upper surface and into a groove 91 of a cam member 92. The cam member 92 is pivotally mounted on the carriage 70 by means of a pivot pin 93 and is held in position with respect to the carriage by means of a retainer plate 94, which has a lip 95 extending over the upper surface of the cam member, the lip 95 being grooved to permit the cam member 92 to be shifted from the position shown by means of an adjustment screw 96. The adjustment screw 96 is threaded into a block 97, which is, in turn, pivoted on a bridging member 98 by means of a pivot pin 99. The bridging member 98 is, in turn, suitably secured to the upper surface of the cam member 92. The shank of the screw 96 has a knurled head portion 100 formed on it and is journaled in a journal block 101, in which the screw is held by a pair of collars 102 and 103. A pivot pin 104 extending downwardly from the journal block 101 extends into a bracket 105, which is fixed to the upper surface of the carriage member 70 and is bent upwardly out of the path of the cam member 92. Suitably fixed to the journal block 101 is a scale plate 106 for cooperation with a pointer 107, which is fixed to the block 97 in any suitable manner.

In the operation of the apparatus, the angle of application of windings on the core 17 may be controlled by adjusting the position of the pointer 107 with respect to the scale plate 106, on which there are suitable lines scribed to indicate the adjusted position of the cam member 92. When the screw 96 is manipulated by means of the head portion 100, the cam member 92 will be displaced about the pivot pin 93, thereby to control the length of the path along which the cam roller 90 will be guided and, consequently, will determine the rate of movement of the slide 76. Since the slide 76 serves to actuate the core supporting block 77, the core will be moved an amount depending upon the angular position of the cam member 92 with respect to the carriage member 70. After a core 17 has been suitably placed in position between the core supporting

block 77 and the core clamping plate 80 and clamped therebetween with the travelling nut 67 in the position shown in Fig. 2, the handle 44 may be manipulated to move the eccentric pin 41 through an eccentric path, thereby to engage the clutch teeth 36 with the clutch teeth 35 and, by moving the shaft 27, to disengage the teeth 46 from the clutch member 45. In this position, the apparatus will be in condition to apply a winding from the winding ring 14 on the straight side of the core 17, which is enclosed in the winding ring, and the motor (not shown) for driving the belt 22 may be started in operation to drive the shaft 13. As the shaft 13 rotates with the clutch member 37 in the position opposite to that shown in Fig. 1, the worm 24 will drive the worm gear 25, thereby to rotate the sleeve 26 and drive the travelling nut 67 to the left (Fig. 2). This operation will continue and the strand from the winding ring 14 will be very accurately applied to the core 17 as the travelling nut 67 moves to the left in timed relation to the rotation of the winding ring. This operation will continue until the travelling nut 67 strikes the lever 65 to operate the switch 63, thus interrupting the operation of the motor after a single layer of strand has been applied to the core. After the motor (not shown) has been stopped and the winding operation, therefore, stops, the strand wrapped on the core 17 may be suitably secured thereto and after the core is removed from the apparatus, the clutch member 37 may be moved to its inoperative position by manipulating a handle 44. This will cause the clutch member 45 to engage with the teeth 46 to condition the apparatus to be returned to normal position, as shown in Fig. 2, by manipulating the handle 50 and rotating the shaft 49 in the proper direction.

40 What is claimed is:

1. A distributor for a winding mechanism comprising a reciprocable carriage, threaded means for driving said carriage, a cam member actuatable by said carriage, a distributor slide actuatable by said cam member, means for pivotally connecting the cam member to the carriage, and means threadedly interconnecting the carriage and cam member to move the cam member about its pivot for adjusting the angular relation of the cam member and distributor slide, said last-mentioned means comprising a bracket fixed to said carriage, a threaded shaft freely rotatable in and fixed against axial movement with respect to said bracket, and a block pivoted on said cam member and threaded to receive the threaded shaft.

2. A distributor for a winding mechanism comprising a reciprocable carriage operable in timed relation to the winding mechanism, threaded means for driving said carriage, a cam member actuatable by said carriage, a distributor slide actuatable by said cam member, means for adjusting the angular position of the cam member with respect to the carriage to determine its effect on the distributor slide, manually operable means for actuating said threaded means, and means shiftable to connect the carriage to the winding mechanism or to the manually operable means, including a shaft slidably with respect to and keyed to said threaded means, and clutch members at opposite ends of said shaft connectible alternately to the manually operable means or the winding mechanism.
